Inventor

Fred W. Henricson,
By A. V. Frank

Attorney

UNITED STATES PATENT OFFICE.

FRED W. HENRICSON, OF PHILADELPHIA, PENNSYLVANIA.

SLOT-CLOSING DEVICE.

Application filed November 13, 1920. Serial No. 423,945.

To all whom it may concern:

Be it known that I, FRED W. HENRICSON, a citizen of the United States, residing at Philadelphia, in the county of Philadelphia and State of Pennsylvania, have invented 5 certain new and useful Improvements in Slot-Closing Devices, of which the following is a specification.

My invention relates to improvements in 10 slot closing devices for closing the slots in the floor boards of automobiles within which the foot and hand operated arms or levers are adapted to be moved longitudinally of the slots.

15 The object of the invention is to provide a slot closing device of novel, simple and efficient construction having a movable member or members held by yielding pressure in a normal position closing a slot and permitting an arm or lever to be moved through 20 the slot longitudinally thereof by moving said member or members from their normal position.

The invention is particularly adapted for 25 use in connection with automobiles of the Ford type for preventing air from entering the body of the car through the slots in the floor thereof through which the hand and foot controlling levers extend. The air entering the car through these slots being objectionably hot during warm or hot weather due to the heat generated by the motor of the car, and being objectionably cold during cool or cold weather.

30 35 The invention aims to provide a device which will substantially close the entire slot when the arm or lever therein is at rest in the normal position which it usually occupies while the car is being driven, and which 40 will partially close the slot when the arm or lever is moved from its said normal position.

With the above and related objects in view, 45 the invention consists in the novel construction, combination and arrangement of parts hereinafter described and claimed.

In the accompanying drawings, illustrating 50 my invention,

Figure 1 is a longitudinal section showing a floor provided with a slot, a lever arm extending through the slot and a slot closing device embodying my invention applied to the floor.

55 Figure 2 is a transverse section thereof, on line 2—2 of Fig. 1.

Figure 3 is a section on line 3—3 of Fig. 1. Figure 4 is a section similar to Fig. 3, showing the lever arm and slot closing members of the device in a different position.

Figure 5 is a section through the central 60 portion of the device, on line 5—5 of Fig. 1. Referring to the drawings, 4 designates a floor having a slot 6 formed therein. The floor 4 is formed in two separable sections 7 and 8 which meet each other, at 9, and the slot 6 extends into each section 7 and 8 and crosses the joint between them.

Extending through the slot 6 is a lever arm 10 adapted to be moved forward and back on a fulcrum 11, and, when thus moved, 70 to move through the slot 6 longitudinally thereof.

Mounted on the floor 4 is a slot closing device constructed in accordance with my invention; and, as herein illustrated, this 75 device is constructed as follows:

The frame or casing 16 of the device is formed by upper and lower plates 12 and 13 which are brazed or otherwise suitably secured thereto, and comprises a base portion 14 and a raised central portion 15. The casing 16 has a slot 17 therein extending centrally through the raised portion 15 from one end of the casing toward the opposite end thereof, and having a closed inner end 85 and an open outer end at one end of the casing. The casing 16 extends over the two sections 7 and 8 of the floor 4 and it is secured to the section 7 by means of screws 18 which penetrate the base 14 and are 90 screwed into the section 7, thus permitting either floor section 7 or 8 to be removed from the other without disturbing the means which secured the casing 16 to the floor.

When the section 7 is removed from the section 8, the casing 16 is removed by and with the section 7; and when the section 8 is removed from the section 7, the casing 16 remains in place upon the section 7. The section 8 is removed from the section 7 by 100 sliding the section 8 out from beneath the casing 16.

The slot 17 in the casing 16 is directly over and in registry with the slot 6 in the floor 4, and the lever arm 10 extends up 105 through the slot 17, as well as through the slot 6, and when the arm 10 is moved on its fulcrum 11, it moves longitudinally through both slots 6 and 17.

When the lever arm 10 is in the normal 110

position, as shown in the drawings, it rests adjacent to the closed end of the slot 17, and that portion of the slot 6 which extends from the arm 10, in the normal position of the arm, is normally closed by two oppositely-disposed, elongated members 19 which are slidably fitted within openings 20 formed in the raised portion of the casing 16 between the plates 12 and 13 on the respective sides 10 of the slot 17. The opposing sides of these members 19 are provided with elongated anti-friction rollers 21 which are journaled in the members 19 and rest normally in contact with each other within the central portion 15 of the slot 17.

The rollers 21 are pressed normally into contact with each other by flat bow springs 22 housed within the openings 20 and having their opposing central portions bearing 20 against the central portions of the members 19 and their respective end portions bearing against the other walls of the openings 20.

The inner end portions of the members 19 25 are made flaring or beveled, at 23, and these beveled end portions 23 rest adjacent to lever arm 10, on the respective sides thereof, when the parts are in the normal position, shown in Figs. 1, 3 and 5; and, when the 30 parts are in this normal position, the slot 17 is closed by the arm 10 and members 19, which also close the slot 6.

When the lever arm 10 is moved forwardly from the position shown in Fig. 3 35 to the position shown in Fig. 4, the arm 10 engages the beveled ends 23 of the members 19 and forces them apart against the action of the springs 22, as the arm 10 moves forwardly through the slots 6 and 17; and after the arm 10 engages the rollers 21, during the forward movement of the arm, the rollers turn and reduce the friction which 40 would occur in the absence of the rollers.

After the lever arm 10 passes the central 45 portions of the members 19, or from between the central portions of the springs 22 which engage the members 19, the springs 22 close the inner ends of the members 19 or move them back into contact with each 50 other rearwardly of the arm 10 and thereby partially close the slots 6 and 17, as shown in Fig. 4.

When the lever arm 10 is moved forwardly only a short distance from the position 55 shown in Fig. 3, it opens only the inner or adjacent end portions of the members 19, the springs 22 holding the outer end portions of the members 19 in the closed position partially closing the slot 17; and the 60 outer end portions of the members 19 are not separated out of contact with each other until the lever arm 10 is moved forwardly beyond the central portions of the members 19.

65 It will now be understood that when the

lever arm 10 is in the normal position, it and the members 19 will substantially close the slots 6 and 17 and prevent air from passing through the slot 6 in the floor 4; and that when the lever arm 10 is moved to 70 many other positions within the slots 6 and 17, the members 19 will partially close the slots 6 and 17 and reduce the area thereof through which air is permitted to pass.

When the section 7 of the floor 4 is removed from the section 8 and from the lever arm 10, the arm 10 will pass between the members 19 and out through the open end of the slot 17.

I claim as my invention:

1. The combination of a floor having a slot therein, an arm extending through said slot and movable longitudinally therein, a casing secured to said floor and having a guide opening therein, a member slidably fitted within said opening and movable into and from a normal position closing a part of said slot and being adapted to be moved from its normal position by said arm when said arm is moved longitudinally within said slot, and means housed within said casing for yieldingly maintaining said member in its normal position.

2. The combination of a floor having a slot therein, an arm extending through said slot and movable longitudinally therein, an elongated member extending lengthwise of the slot adjacent thereto and being movable into and from positions closing parts of said slot and being adapted to be moved from said positions by said arm when said arm is moved longitudinally within said slot, and yielding means acting upon the central portion of said member and tending to hold it in said positions, said member being adapted to be rocked on said yielding means, permitting one end portion of said member to remain in a position closing a part of said slot while said arm moves the other end portion thereof away from a position closing a part of 110 said slot.

3. The combination of a floor having a slot therein, an arm extending through said slot and movable longitudinally therein, and two oppositely disposed members extending lengthwise of the slot and being movable toward and from each other into and from positions closing parts of said slot and being adapted to be separated by said arm when it is moved longitudinally within said slot thereby moving said members from said positions, each member being provided with yielding means pressing it toward the other member.

4. The combination of a floor having a slot therein, an arm extending through said slot and movable longitudinally therein, and two oppositely disposed members extending lengthwise of the slot and being movable toward and from each other into and from 130

positions closing parts of said slot and being adapted to be separated by said arm when it is moved longitudinally within said slot thereby moving said members from said 5 positions, each member being provided with yielding means pressing it toward the other member, and said members having outwardly flared ends adjacent to said arm in the normal position thereof adapted to be engaged by said arm when it is moved for the separation of said members.

5. The combination of a floor having a slot therein, an arm extending through said slot and movable longitudinally therein, and 10 two oppositely disposed members extending lengthwise of the slot and being movable toward and from each other into and from positions closing parts of said slot and being adapted to be separated by said arm 15 when it is moved longitudinally within said slot thereby moving said members from said positions, each member being provided with yielding means pressing the central portion thereof toward the central portion of the other member, said members being adapted 20 to be rocked on their yielding means permitting adjacent end portions thereof to remain in positions closing parts of said slot while said arm moves the other end portions thereof away from positions closing parts of said 25 slot, and said members having outwardly flared ends adjacent to said arm in the normal position thereof adapted to be engaged by said arm when it is moved for the separation of said members.

thereof away from positions closing parts 30 of said slot.

6. The combination of a floor having a slot therein, an arm extending through said slot and movable longitudinally therein, and two oppositely disposed members extending 35 lengthwise of the slot and being movable toward and from each other into and from positions closing parts of said slot and being adapted to be separated by said arm when it is moved longitudinally within said slot 40 thereby moving said members from said positions, each member being provided with yielding means pressing the central portion thereof toward the central portion of the other member, said members being adapted 45 to be rocked on their yielding means permitting adjacent end portions thereof to remain in positions closing parts of said slot while said arm moves the other end portions thereof away from positions closing parts of said 50 slot, and said members having outwardly flared ends adjacent to said arm in the normal position thereof adapted to be engaged by said arm when it is moved for the separation of said members.

55 In testimony whereof I affix my signature hereto.

FRED W. HENRICSON.
